CLAIM

I claim the ornamental design for a nicotine inhaler, as shown and described.

DESCRIPTION

FIG. 1 is a top perspective view of my new design for a nicotine inhaler;

FIG. 2 is a another top perspective view thereof;

FIG. 3 is a front perspective view thereof;

FIG. 4 is a left side perspective view thereof;

FIG. 5 is a top view thereof;

FIG. 6 is a right side view thereof;

FIG. 7 is a bottom view thereof;

FIG. 8 is a left side view thereof;

FIG. 9 is a front view thereof; and,

FIG. 10 is a rear view thereof.

The broken lines in the drawings depict portions of the nicotine inhaler and form no part of the claimed design.

1 Claim, 7 Drawing Sheets
